UNITED STATES PATENT OFFICE.

ROLLIN HENRY WHITE, OF CLEVELAND, OHIO, ASSIGNOR TO THE WHITE SEWING MACHINE COMPANY, OF SAME PLACE.

DESIGN FOR A GAS-BURNER.

SPECIFICATION forming part of Design No. 33,794, dated December 25, 1900.

Application filed December 3, 1900. Serial No. 38,569. Term of patent 14 years.

To all whom it may concern:

Be it known that I, ROLLIN HENRY WHITE, a citizen of the United States, residing at Cleveland, in the county of Cuyahoga and State of Ohio, have invented and produced a new and original Design for a Gas-Burner, of which the following is a specification, reference being had to the accompanying drawings, forming part thereof.

In the drawings, Figure 1 is a plan of my burner; Fig. 2, a vertical section thereof on the line 2 2 of Fig. 1. Fig. 3 is an edge view.

The leading or material features of my design consist of a plate having a series of concentric curved hollow ridges transversely slotted and between these ridges a series of openings and on the under side of the plate a hollow box having openings in its bottom alined with the openings through the top plate, there

being tubular connections between such 20 alined openings.

Referring to the parts by letters, A represents the top plate; B, the curved ridges; C, the slits therein; D, the box below the plate, and E the tubular connections between the 25 alined holes in the top and bottom.

Having described my invention, what I claim as new, and desire to secure by Letters Patent, is—

The design for a gas-burner substantially 30 as herein shown and described.

In testimony whereof I hereunto affix my signature in the presence of two witnesses.

ROLLIN HENRY WHITE.

Witnesses:

F. D. AMMEN,
ALBERT H. BATES.
